INVENTOR.

LOUIS A. BEAN

R. J. Collethatt
ATTORNEY.

UNITED STATES PATENT OFFICE.

LOUIS A. BEAN, OF DENVER, COLORADO, ASSIGNOR TO CLIVE L. SENTER, OF DENVER, COLORADO.

AUTOMATICALLY-CONTROLLED SPOTLIGHT.

Application filed April 25, 1922. Serial No. 556,503.

To all whom it may concern:

Be it known that I, LOUIS A. BEAN, a citizen of the United States of America, residing at Denver, in the county of Denver and State of Colorado, have invented certain new and useful Improvements in Automatically-Controlled Spotlights, of which the following is a specification.

This invention relates to a spot-light which is adapted to be controlled by the movements of the front wheel spindle of an automobile and has for its principal object the provision of a device of this character which can be attached without the necessity of drilling holes or disturbing the present headlights in any way.

Another object is to provide an article of this character which will be supported above the car springs and which will not be subjected to the vibrations of the axle.

A further object is to provide a spot-light which will automatically follow the movements of the front wheels of the automobile and keep the road ahead lighted regardless of turns in the road.

A further object is to provide a light near the surface of the road below the head lights, which will project a beam along the road where needed and yet will be so low that the direct beam of light will not strike the eye of an approaching autoist.

A still further object resides in the provision of a device of this character which can be easily adjusted to suit various spring heights on different cars and in which the direction of the beam of light is easily adjustable and which is also adjustable to hold different present makes of spot-lights.

A still further object is to provide bearings and joints which are enclosed to prevent mud, sand, water, etc., from reaching the bearing surfaces.

Other objects reside in the detail construction of the article which lead to efficiency, simplicity and cheapness of manufacture and which will become apparent from the following description.

The invention will now be described in detail with reference to the accompanying drawing which forms a part hereof, corresponding and like parts are referred to in the following description and in all views of the accompanying drawing by the same reference characters.

In the drawing:

Fig. 1 is a fragmentary perspective view of the improved spot-light installed on an automobile.

Fig. 2 is a partial front view of an automobile with the improved spot-light in place.

Fig. 3 is a plan view of the device with a cross section taken on the line 3—3, Fig. 4.

Fig. 4 is a side elevation of the spot-light and supporting mechanism.

Fig. 5 is a detail view of the lever arm which is adapted to be attached to the steering spindle of an automobile.

Fig. 6 is a detail view of a modified form of the lever arm shown in Fig. 5.

Fig. 7 is a detail view of the radius rod which transmits the action of the steering spindle to the spot-light.

Let the numeral 10 designate a supporting arm which is provided at its upper extremity with a clamp 11 adapted to be clamped to one of the head-light brackets of certain automobiles as shown at 12, Fig. 1. The lower extremity of supporting arm 10 is provided with a vertical sleeve 13 in which is slidably mounted a section of tubing 14. Tubing 14 is locked in position in the sleeve 13 by means of a set screw 15.

Rotatably mounted in the tubing is a section of smaller tubing or a rod 16, carrying, fixed to its upper extremity, a bifurcated clamp 17, and to its lower extremity a lever arm 18. Clamp 17 and lever 18 may be fixed to rod 16 by means of pins 19, or in any other suitable manner, and are so placed that they fit snugly against the ends of tubing 14, thereby preventing the entering of foreign substances between the rod 16 and the tubing 14.

Fitted into the bifurcation in the clamp 17 is a spot-light clamp 20, which is adapted to be slipped over the stem or handle of a spot-light 21 and clamped thereon by means of a clamp-screw 22.

Spot-light clamp 20 can be rotated in the clamp 17 so as to direct the beam of the spot-light at any desired vertical angle.

Lever arm 18 is provided near its free extremity with a ball socket, 23, adapted to receive a ball 24 fixed on one extremity of a radius rod 25. When ball 24 is in place, ball socket 23 is covered by means of cap 26 which is shaped on its inner side to conform to the shape of the ball socket 23. Cap 26

is provided with a large circular opening 27 to allow free radial play for the radius rod 25 and in addition is provided with a slot 28 which allows a greater horizontal movement 5 of the lever 18 in relation to the radius rod 25.

Radius rod 25 is provided at its opposite extremity with a ball 29 similar to the ball 24. Ball 29 is adapted to rest in a ball socket 10 formed in a second lever 30 and to be held therein by a ball socket cap 31. Both the lever 30 and the cap 31 are slotted as shown at 32, in Figs. 5 and 6, to allow horizontal radial movement of the radius rod 25.

15 Caps 26 and 31 clamp the balls 24 and 29 respectively with sufficient firmness to prevent any rattling but still allow free movement of the balls in their sockets. Any looseness can be taken up by tightening the 20 screws which hold the caps to the levers.

25 Lever 30 is provided with a shoulder or flap 33 which is adapted to fit under the spindle arm nut 34 of an automobile. The contour of the extremity of lever 30 is such that it fits around the automobile spindle body 35 as shown in Fig. 3, where the usual automobile spindle body is shown in broken lines.

30 In Fig. 6 a modified form of the lever arm 30 is shown, which will be designated as 30^a. This form is used where it is desired to raise the radius rod for any reason.

35 For most efficient operation and to prevent the vibrations of the axle from being transmitted to the spot-light the radius-rod 25 is kept absolutely horizontal. Different automobiles of the same make, because of different weights and spring conditions vary in height from the axle to the chassis. Adjustment for these varying conditions is 40 made by sliding the tubing 14 in the socket 13, until the radius rod 25 is horizontal, and then locking it in place with the set screw 15.

45 The operation of the device is so evident from the foregoing description and drawing that a detailed explanation thereof is not deemed necessary.

50 While I have described and illustrated herein a specific form of my invention I wish it understood that the same may be varied within the scope of the appended claims without departing from the spirit of the invention.

Having thus described my invention, what I claim and desire to secure by Letters Patent is:—

65 1. An automatically controlled spot-light comprising a lever adapted to be attached to the front wheel spindle of an automobile; an arm adapted to be attached to the head-light supporting stem of an automobile; a spot-light mounted on a vertical shaft, said shaft being adapted to rotate in said arm; a second lever mounted on said shaft and means for pivotally connecting said second lever with said first mentioned lever.

70 2. An automatically controlled spot-light comprising a lever adapted to be attached to the front wheel spindle of an automobile; an arm carrying at its one extremity a clamp for engaging the stem of the automobile head-light and at its other extremity a vertical sleeve; a tubing mounted in said sleeve so as to be vertically adjustable therein; a spot-light carrying shaft rotatably mounted in said tubing and provided at its lower extremity with a fixed lever and means for pivotally connecting said fixed lever with said first mentioned lever.

75 3. In an automatically controlled spot-light, the combination of an L shaped arm adapted to be clamped to an automobile head-light bracket at its one extremity and provided with a vertical sleeve at its opposite extremity; a tubing slidably mounted in said sleeve; means for securing said tubing at any desired point in said sleeve; a spotlight-supporting shaft rotatably mounted in said tubing and means for communicating the movements of the automobile steering mechanism to said shaft.

80 4. Means for mounting an automatically controlled spot-light comprising an arm arranged to clamp to the head-light supporting stem of an automobile and project downwardly and forwardly therefrom, said arm being provided at its forward extremity with a vertical sleeve in which is slidably mounted a vertical tube, said tube acting as a bearing for the spot-light stem and means for securing said tubing at any desired height in said sleeve.

85 In testimony whereof I affix my signature.

90 LOUIS A. BEAN.
